UNITED STATES PATENT OFFICE.

ROBERT C. STEVENS, OF ERIE, PENNSYLVANIA.

STEAM-HEATED PISTON.

1,312,285.

Specification of Letters Patent.

Patented Aug. 5, 1919.

Application filed December 17, 1917, Serial No. 207,572. Renewed June 7, 1919. Serial No. 302,594.

To all whom it may concern:

Be it known that I, ROBERT C. STEVENS, a citizen of the United States, residing at Erie, in the county of Erie and State of Pennsylvania, have invented certain new and useful Improvements in Steam-Heated Pistons, of which the following is a specification.

This invention relates to means for heating the pistons of steam engines, and involves a construction in which steam is admitted into the interior of a hollow piston from a source of steam supply, and circulating through said piston is discharged therefrom, at some time in its stroke, and may be conducted back to the steam supply chamber for power purposes. The present construction has the advantage that the water of condensation does not have to be lifted from the lower part of the piston, but the flow thereof is in the direction of the natural gravity flow.

The steam is admitted to the piston from a chamber on the cylinder head which communicates through a hollow tail rod on the piston with the interior of the latter, and the discharge from the piston takes place through a port in the lower part of the piston wall which registers at intervals with an outlet or return pipe.

In one form of the invention the outlet pipe opens through the cylinder wall between spaced rows of main exhaust ports extending around the cylinder, so that the piston always laps the outlet passage from the piston, but alternately uncovers the respective rows of main exhaust ports, the engine in this case being of the double acting uniflow type. Modifications are possible, enabling the invention to be applied to a uniflow engine having a single row of exhaust ports; and the invention may also be applied to counterflow engines, and no limitation in this respect is implied by reason of the fact that the invention is illustrated and described as a uniflow.

In the accompanying drawings,—

Figure 1 is a longitudinal vertical section of an engine provided with the invention. Fig. 2 is a cross section on the line 2—2 of Fig. 1.

Fig. 3 is a section of a modification showing a different manner of supplying steam to the piston.

Fig. 4 is a similar view of another modification.

Fig. 5 is a similar view in which only one row of main exhaust ports is shown.

Referring specifically to the drawings, A indicates the cylinder of a double acting uniflow engine having a middle exhaust belt J with which two spaced rows of exhaust ports K communicate. These ports are arranged in rows extending around the cylinder. B is a hollow head which forms a steam chamber containing the inlet valve B' to the cylinder. C is the piston and D is the piston rod connected thereto. The piston is hollow, and the piston rod is extended to form a tail rod D' extending through the cylinder head and projecting into a steam chamber G fastened to the cylinder head. The tail rod D' is bored lengthwise as indicated at E and this passage communicates at its inner end through a port F with the interior of the piston. The port H connects the steam space in the head B with the chamber G, and a small port I is located in the lower part of the chamber for the purpose of drainage. The tail rod works through a packing gland in the cylinder head as shown.

The lower side of the circumferential wall of the piston is provided near each end with an outlet port M which may be notched to give a longer time for out flow. One of these ports M registers at the end of stroke in each direction with a port N at the middle of the cylinder, between the two rows of main exhaust ports K and the port N connects to a return pipe P which leads to the steam space in the cylinder head B. Q is a drain cock, and O are packing rings around the piston, outside of the ports M.

In the operation of this type, the head B and chamber G contain steam at boiler pressure, and this steam flows into the interior of the piston through the tail rod D' and port F. At about the end of each stroke one of the ports M registers with the port N and the steam and water of condensation can flow from the interior of the piston through the pipe P to the bottom of the steam chamber in the head B, the water flowing by gravity. By making the ports H and I rather small, a slight building up of the pressure in the chamber G is effected by the displacement of the tail rod when the piston moves toward the right as shown in Fig. 1, and when the piston is in motion the inertia of the water of condensation will tend to throw it at the end of each stroke to the

proper end of the piston for its discharge through the port N. That is, when the piston is in motion the water will flow toward the rear end thereof, in position to escape through the ports M and N when they register at the end of the stroke. Therefore gravity, inertia and the impulse of the stroke all operate to assist a flow of steam at throttle pressure through the piston and out at the port N and back into the cylinder head, and thus flow may be produced by these forces without the assistance of check valves, consequently there is an intermittent impulse and flow of steam from the steam supply chamber through the piston and back to the chamber, the water of condensation passing out at the same time.

It should be noted that the ports M are located out of line with the ports K, so that they do not register therewith at any time. This is readily effected by locating the ports M in line with the "bridges" between ports K. The packing rings O prevent the escape of any steam from the cylinder to the outlet port N, and by reason of the location of the port N between the two rows of ports K, the former is lapped by the piston at all times and the latter are alternately opened and closed by the reciprocation of the piston.

In the modified form shown in Fig. 3, the tail rod chamber G, instead of being supplied with steam through ports such as H, is supplied with steam through a pipe S which communicates with the main steam supply pipe I, the pipe S having a bell mouth R presented toward the direction of flow in the steam pipe, whereby, at each rush of steam incident to the opening of the inlet valve B', an impulse of steam is produced through the pipe S and into the chamber G and continuing through the piston which at that time is at the dead center with the ports M and N in register.

In the modification shown in Fig. 4, a check valve V is provided at the port H, and a check valve U at the port N, and these check valves will assist the flow through the piston, because when the tail rod D' travels to the right the check valve V will close because of the increased pressure in the chamber G, giving a pumping action which will force a flow through the piston and through the valve U which is thereby opened.

In the modification shown in Fig. 5 the valves V and U are also used, but instead of a double row of ports K a single row only is provided, and only one port M which regis-

ters with the port N at the end of each stroke in one direction, but not in the other direction. There is no danger that, in this form, the valve U will be opened when it is uncovered by the piston, because the pressure in the cylinder will then be much less than the pressure on the other side of the valve U communicated from the hollow head through the pipe P.

I claim:

1. The combination with a steam engine cylinder and a hollow piston therein, of a steam chamber on the cylinder head, a hollow tail-rod projecting from the piston and communicating with the interior thereof and working through the cylinder head into said chamber, and a return pipe communicating with said chamber and having a port in the cylinder wall, the piston wall having a port which registers with said port at a certain time during the stroke of the piston, to permit outflow from the piston to said pipe.

2. The combination with a steam engine cylinder and a hollow piston therein, of a steam chamber at the head of the cylinder, a hollow tail rod on the piston working through the cylinder head and communicating at its outer end with said chamber and at its inner end with the interior of the piston, said piston having an outlet port in the lower wall thereof, and a return passage communicating at one end with the steam supply to the cylinder and having a port through the cylinder wall with which the port in the piston registers at about the end of the compression stroke of the piston.

3. The combination with a steam engine cylinder having a steam supply passage thereto, and a hollow piston in the cylinder, of a steam chamber on the cylinder head communicating with said passage, a hollow tail rod projecting from the piston, through the cylinder head and into said chamber, said piston having a port in the wall thereof, and a return pipe communicating at one end with said supply passage and having a port at the other end into the cylinder and with which the port in the piston registers at about the end of the compression stroke of the piston.

In testimony whereof, I affix my signature in presence of two witnesses.

ROBERT C. STEVENS.
